UNITED STATES PATENT OFFICE.

CHARLES COSTANZ, OF BROOKLYN, NEW YORK.

DESIGN FOR A LAMP GLOBE.

Application filed August 2, 1922. Serial No. 3,287. Term of patent 14 years.

To all whom it may concern:

Be it known that I, CHARLES COSTANZ, a citizen of the United States, residing at 2016 West 5th Street, in the borough of Brooklyn, county of Kings, city and State of New York, have invented a new, original, and ornamental Design for a Lamp Globe, of which the following is a specification, reference being had to the accompanying drawing, forming part thereof.

Fig. 1, is a top view, and Figs. 2 and 3

are side elevations of a lamp globe, showing my new design, the colors being represented symbolically.

I claim:

The ornamental design for a lamp globe, as shown.

CHARLES COSTANZ.
